UNITED STATES PATENT OFFICE.

JOSEPH LUSTIG, JR., OF JANEVILLE, WISCONSIN.

TOY.

Application filed September 18, 1922. Serial No. 588,947.

To all whom it may concern:

Be it known that I, JOSEPH LUSTIG, Jr., a citizen of the United States, and resident of Janesville, in the county of Rock and 5 State of Wisconsin, have invented certain new and useful Improvements in Toys; and I do hereby declare that the following is a full, clear, and exact description thereof.

The invention relates to toys of a whirligig type. It comprises a pair of supports 10 simulating sections of a wall, a pair of balanced toy-like figures, and resilient means supporting the figures adapted on the rotation of the toy-like figures, which is initiated 15 manually, to store up power and to reverse the direction of rotation of the figures.

A primary object of the invention is the provision of means adapted to prolong the rotation of the toy-like figures. Rubber 20 bands are provided and when the figures are rotated, the bands are twisted, thus storing up power. The twisted bands reverse the direction of travel of the toy-like figures so that the movement is continued for a 25 long period. The toy-like figures are egg shaped and painted to simulate men. The movement of the egg shaped figures thru the wall is suggestive of the nursery 30 rhymes of Humpty Dumpty, and is adapted to entertain children.

An important object of the invention is the provision of means for holding the toy-like figures in a substantially horizontal position when stationary.

A further object is the provision of a construction that is simple and easy to manufacture, being made of a minimum number 35 of parts.

With the above and other objects in view 40 which will appear as the description proceeds, the invention resides in the novel construction, combination and arrangement of parts substantially as hereinafter described and more particularly defined by 45 the appended claims, it being understood that such changes in the precise embodiment of the herein disclosed invention may be made as come within the scope of the claims.

In the accompanying drawing, is illustrated 50 one complete example of the physical embodiment of the present invention constructed according to the best mode so far devised for the practical application of the principles thereof.

Figure 1 is a side elevation of the device.

Figure 2 is an end elevation.

Figures 3 and 4 are detail.

Base members 1—1' extend throughout the entire width of the device and are secured to opposite faces of aligned supports 2—2' which simulate a wall, and are broken away to form an opening 3. The base members make a rigid connection between the supports, facilitating the transportation 60 of the toy from place to place. Secured to opposite faces of the upper ends of each of the supports are top pieces 4—4' thru each pair of which is directed a transverse pin 5—5'. Pin 5 supports elastic band 6, and pin 5' supports elastic band 6'.

Secured to the ends of the band is a metallic clip 7, provided with downwardly directed flanges 7'—7'', each of the flanges being provided with a notch 7''' receiving and 75 securely retaining the rubber band. The clip is bowed centrally and secured to an elongated rod 8 by means of a screw 8'. The rod is secured at its ends to egg shaped figures 9—9', which are painted to simulate 80 men. One of the figures may be struck by the hand, thus causing a rotation of the pair and a twisting of the elastic band 6—6'. The rotary movement of the figures continues for some time, the elastic bands storing 85 up power. On the cessation of rotation of the figures in one direction, the band operates to turn them in reversed movement. Thus the rotation is continued for 90 some time. The figures, when not moving, are maintained normally in a horizontal position indicated by dotted lines in Figure 2.

The flanges 7'—7'' have a relatively large 95 vertical dimension. By reason of the tendency of the elastic bands to maintain themselves in an untwisted condition, there is a cooperative relationship between the bands and the flanges tending to hold the flanges in such position that the figures 9—9', when not in motion, are held horizontal. The design of the egg shaped figures, and the supports 2—2', which simulate a wall, are suggestive of the nursery rhymes of Humpty Dumpty. The movement of the figures, therefore, is especially amusing to children. 100 The size of the opening 3 is such as to permit free movement of the toy-like figures therethru.

A pair of rectoparallelepipedal casings 110 10—10' are provided, having open inner ends and bottoms. Each of the casings fits upon a pair of top members 4—4'. In Fig-

ure 1, casing 10 is shown in outer position. It may be slid inwardly to a position similar to that of casing 10'. It then operates to cover the elastic band 6, and the end of 5 clip 7, thus the operative mechanism is concealed from view.

If desired, the center of gravity of the figures 9—9' may be lowered to lie normally below the pivot point. This tends to 10 maintain the figures erect in the position shown in dotted lines in Figure 2.

While I have illustrated and described one specific form in which the invention may be designed, such as figures simulating 15 Humpty Dumpty mounted on a wall, it will be readily understood that various modifications are contemplated as within the scope of the appended claims, the primary feature of the invention residing in the means 20 for prolonging movement imparted to the suspended figures.

Claims:

1. The combination of a pair of toy-like objects, a rigid member extending between 25 and secured to said objects, a clip on said rigid member, a flange on one end of said clip, a second flange on the other end of said clip, a support, a second support, a rubber

band secured to said first mentioned support at one end and at the other end to said 30 flange, and a second rubber band secured at one end to said second support and at the other end to said second flange, said rubber bands extending in a substantially horizontal line, said flanges having a relatively 35 large normal vertical dimension, whereby said objects, when in rest, are supported horizontally.

2. A toy comprising a base, a wall extending vertically upwardly therefrom and 40 formed of two opposite portions providing a space therebetween, a rubber band secured to each of said portions and extending inwardly, a bar attached adjacent its center to said rubber bands and adapted to swing in 45 a vertical plane, and a toy like object carried at each end of said bar, whereby said bar will rock in a vertical plane and cause 50 said objects to travel above and below the upper edge of said wall.

In testimony that I claim the foregoing I have hereunto set my hand at Janesville, in the county of Rock and State of Wisconsin.

JOSEPH LUSTIG, JR.
